UNITED STATES PATENT OFFICE.

DANIEL B. TAMAGNO, OF NEW YORK, N. Y., ASSIGNOR TO LYDIE TAMAGNO, OF NEW YORK, N. Y.

SPOUT-CLOSURE FOR CANS.

1,056,855.

Specification of Letters Patent. Patented Mar. 25, 1913.

Application filed April 22, 1912. Serial No. 692,859.

To all whom it may concern:

Be it known that I, DANIEL B. TAMAGNO, a citizen of the United States of America, residing in New York city, in the borough 5 of Manhattan, county and State of New York, have invented a new and useful Improved Spout-Closure for Cans, of which the following is a specification.

This invention relates to a rocking discharge spout for cans, so arranged that 10 when in normal depressed non-pouring position outlet from the can is closed and when the spout is rocked into pouring position it is placed in communication with the 15 interior of the can. Furthermore the rocking spout is located in a countersink or pocket in the top or side of the can and when in normal inoperative position is depressed below or flush with the side or wall 20 of the can.

The invention consists in certain details of construction hereinafter set forth.

In the accompanying drawing: Figure 1, is an elevation of the upper portion of a 25 cylindrical can, partly broken away, showing the device in section, on the line A B of Fig. 2; Fig. 2, a top plan view with the spout in retracted or closed position; Fig. 3, an enlarged section on line C D of Fig. 1; Fig. 4, an enlarged section on line E F of Fig. 1, Fig. 5, a vertical sectional view of a modified form of the device; and Fig. 6, a partial sectional view on line G H of Fig. 5. 30 Fig. 1 indicates a can into a wall of which is received a spout 2 housed in a pocket 3, comprising the two side parts 4 and 5 joined by a soldered lap joint 6 along the center line. The spout 2 is likewise composed of two die formed parts 7 and 8 joined and 35 soldered by a lap seam 9 along the center line thereof.

The spout has formed at one end a cylindrical portion 10 the axis of which is at 40 right angles to the tube or spout proper and the ends of the cylindrical portion 10 are closed but are provided with openings 11, 11. Cupped recesses or sockets 12, 13 are formed in the sides 4 and 5 of pocket 3 and serve as bearings for the ends of the 45 cylindrical portion 10 of spout 2. Interposed between the ends of the cylindrical portion of the spout and the recesses 12 and 13 are shallow cup-shaped washers 15, 15 composed of leather or other suitable material.

Openings 16, 16 are provided in the end walls of sockets 12, 13 of the pocket and are adapted to register with the openings 11, 11 in the ends of cylindrical portion 10 of the spout when the latter is in the open 60 or pouring position shown by dotted lines in Fig. 1 and in full lines in Fig. 4. The openings 16, 16 in sockets 12 and 13 are formed with inwardly projecting edges 17, 17, that fit snugly in corresponding holes 65 provided in washers 15, 15 but said edges are of less height than the thickness of the washers.

In practice the parts 7 and 8 of the spout are assembled and the joint 9 closed with 70 solder or otherwise and the cupped washers 15, 15, are pressed into the sockets 12 and 13, care being taken to have the projecting edges 17, 17, of holes 16, 16 fit into the holes 75 provided in the washers. The ends of the cylindrical portion 10 of spout 2 are seated in the cupped washers 15, 15 and the two parts 4 and 5 of pocket 3 are pressed tightly together against the spout and so held until 80 the lap joint 6 has been securely sealed with solder or otherwise. The assembled pocket and spout are slipped into a suitable aperture in the top or side of the can and a soldered joint 18 made between the flange 85 19 of pocket 3 and the can.

From Figs. 1 and 3, it will be seen that exit of any liquid in the can, will be prevented when the spout 2 is in its retracted or nested position, as in this position the holes 11, 11 in spout 2 are out of register 90 with the holes 16, 16, in the pocket 3, and the washers 15, 15 will form a seal between the two sets of holes. When, however, the spout 2 is rotated to the dotted position in Fig. 1 and full line position of Fig. 4 the 95 holes 11, 11 in it and holes 16, 16, in pocket 3 are in register and liquid contained in the can may be caused to flow through the spout.

Figs. 5 and 6 show a modification. Bearings or seats 24 and 26 are provided in the 100 side parts 4 and 5 of pocket 3 and an enlarged concentric seat 20 is formed in its end to receive a washer 25. An aperture 22 is provided in the seat 20 and formed 105 with projecting edges 23 over which an opening in washer 25 fits. The cylindrical portion 10 of spout 2 is provided with a corresponding opening 21 designed to register with the aperture 22 when the spout is 110 in the extended position shown in full lines 116

in Fig. 5, and to be out of register when the spout is in its nested or closed position shown by dotted lines in Fig. 5 and full lines in Fig. 6.

5 Any suitable means, not shown, may be used to seal the spout in its nested position until received by the purchaser, such for instance as a piece of thin tin soldered across the pocket 3 directly over the spout 2.

10 It will be understood that the location of the pocket and spout is not confined to the top of the can. There may be permanent connection between the rotative part of the spout and the interior of the can in which 15 case an ordinary cock should be placed in the spout.

I claim:

1. A can having a chamber recessed in one of its walls said chamber having in opposite 20 walls circular concentric bearing surfaces with apertures therein, combined with a spout having a cylindrical portion whose axis is at right angles to the spout and coincident with that of said bearing surfaces 25 and which has in its closed ends apertures that are cut off from the apertures in the bearing surfaces when the spout is turned within the chamber and are open thereto when the spout is turned to pouring position.

30 2. A can having a chamber recessed in one of its walls said chamber having in opposite walls circular concentric bearing surfaces with apertures therein, combined with 35 a spout having a cylindrical portion whose axis is at right angles to the spout and co-

incident with that of said bearing surfaces and which has in its closed ends apertures that are cut off from the apertures in the bearing surfaces when the spout is turned 40 within the chamber and are open thereto when the spout is turned to pouring position and an apertured washer interposed between each bearing surface and corresponding end of said cylindrical portion and held 45 by projecting edges of apertures in one of said parts, that extend into apertures in the washer.

3. A can having a chamber recessed in one of its walls such chamber having in one of 50 its walls a circular concentric bearing surface with apertures therein combined with a spout having an enlarged portion or head whose axis is at right angles to that of the spout and co-incident with that of said bearing surface, one end of said enlarged portion of the spout having apertures therein and having its bearing in the bearing surface of the wall of the chamber the construction and arrangement being such that the 55 two sets of apertures are cut off from each other when the spout is turned within the chamber and are open to each other and to the spout when the latter is turned to pouring position.

60 In testimony whereof, I have hereunto subscribed my name.

DANIEL B. TAMAGNO.
